UNITED STATES PATENT OFFICE.

CLARENCE B. FOWLER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed August 12, 1925. Serial No. 49,742.

This invention relates to telephone systems and more particularly to improvements in the means for interconnecting incoming and outgoing lines at an exchange.

In telephone systems including trunk lines or cord circuits for the completion of connections, a trunk line, outgoing from a tandem office or from an "A" operator's position, may be selected by an "A" operator for the extension of a connection to a "B" operator's position at a distant exchange. On the engagement of such trunks, the "B" operator's telephone set may be automatically connected to the incoming ends of engaged trunks in numerical sequence rather than in the order in which they become engaged. As the telephone set becomes connected to an engaged trunk and the "B" operator receives the number of the wanted subscriber, she inserts the plug of the corresponding trunk into the jack of the wanted subscriber's line. In systems of this type, the tip and ring conductors at the incoming end of the trunks are usually connected to ground and battery respectively and when this end of a trunk is connected with a subscriber's line, changes take place in the circuit arrangements of the trunks to transfer the tip and ring conductors from said ground and battery connections to corresponding ground and battery connections on the tip and ring conductors of the subscriber's line. Ordinarily it is essential that this transfer should be done without interruption or break in the electrical circuit from the battery and ground through these conductors, as at the originating office the trunk may be connected in various manners well known in the art to maintain through this electrical circuit certain circuit connections essential for the maintenance of the connection from the calling subscriber's line.

It is an object of this invention to provide improved means applicable to systems of the above and similar types for insuring that the transfer of the battery and ground connections from a trunk to a connected line takes place without interruption in the continuity of flow of current through the tip and ring conductors of the trunk.

In systems heretofore provided, if the operator inserts the plug of a trunk into a line jack slowly or only partially, it might happen that the circuit through the sleeve terminals of the plug and jack will be com-

pleted prior to the connection between the respective tip and ring terminals thereof to cause circuit changes to take place that would remove the battery and ground connections from the tip and ring conductors of the trunk before these conductors are connected through to the subscriber's line and thus cause a momentary break in the continuity of the electrical circuit through the trunk conductors.

65

Therefore, to attain the above and other objects of the invention as will hereinafter appear, there is provided in accordance with one feature of the invention, means whereby even though the sleeve circuit may be connected through prior to the tip and ring connections on the insertion of a plug into a jack, the battery and ground transfer does not take place until after the tip and ring connections have been made and battery and ground have actually been found present on the connected line.

70

In the accompanying drawings, Fig. 1 shows the incoming end of a trunk circuit terminating at a "B" operator's position and a portion of a sequence circuit whereby the "B" operator's telephone set may be connected to engaged trunks in succession and also the outgoing end of a trunk or subscriber's line whereby a call incoming over the trunk may be extended beyond, while Fig. 2 shows a "B" operator's telephone set and a circuit arrangement for associating it with the sequence circuit.

75

To make clear the functions of the invention as applied to a trunking arrangement of this type, a detail description will be made of a connection established over the trunk 5 to subscriber's line 6 from a distant office (not shown) at which the outgoing end of the trunk terminates and where the connection is completed in any well known manner from the calling subscriber's line. In this description it will be pointed out; besides, how the battery and ground connections are transferred; how the "B" operator's telephone set 100 is automatically connected to engaged trunks in the order in which they are numbered or arranged in the sequence circuit 10 and in particular the connection of the telephone set to trunk 5. It will also be pointed out how a peg-count meter 101 is operated to register the engagement of trunk 5 at the time the operator's telephone set is released from said engaged trunk; such re-

lease taking place when plug 11 of trunk 5 is inserted in jack 12 of the subscriber's line 6. It should be understood that this invention is not limited in its application to this particular type of system but may equally well be applied to other systems such as plug-ending cord circuits with which an operator's telephone set may be automatically or manually associated.

Assuming then that a connection is desired over trunk 5 and that an "A" operator at the distant end of this trunk has caused the tip and ring conductor thereof to be connected together in the usual manner to signal the "B" operator that a connection is desired, the following circuit would be completed: Battery, lower outer armature and back contact of relay 15, lower winding of relay 16, ring conductor of trunk 5 over the loop at an "A" operator's position to the tip conductor of trunk 5 through the upper winding of relay 16 and upper inner armature and back contact of relay 15 to ground. This causes the operation of relay 16 which in operating closes an obvious circuit for relay 17 and also closes a circuit for the lighting of the guard lamp 18 as follows: Battery, lamp 18, resistance 23, lower inner armature and back contact of relay 15, lower outer armature and back contact of relay 20, armature and front contact of relay 16 to ground. The lighting of lamp 18 indicates to the "B" operator, at which position trunk 5 terminates, that a connection is desired over this trunk. The operation of relay 17 completes connections to the sequence circuit 10, such as a connection from ground at its upper armature and front contact to lead 21 and a connection from battery at its lower armature and back contact to lead 22.

A description of this sequence circuit 10 will now be made. In case the operator's telephone set 100 is not connected at the time to any other engaged trunk it will be immediately connected to trunk 5. The first operation towards accomplishing this will be the operation of relay 25 over the following circuit, if it is assumed that trunk 5 is number one of the trunks that may be connected to the operator's telephone set. Battery 35, winding of relay 25, conductor 21, lower armature and back contact of relay 19, upper armature and front contact of relay 17 to ground. The operation of relay 25 closes an energizing circuit for relay 26 as follows: battery, winding of relay 26, armature and front contact of relay 25, make-before-break contacts of relays 25' and 25'' to ground at 27. The operation of relay 26 extends through the operation of its armatures, the tip and ring leads of trunk 5 to the common leads 29 and 30, respectively. It also connects lead 22 to a common lead 31, lead 33 from lamp 18 to a common lead 34 and opens a connection from battery 35,

through its lower inner armature and back contact to corresponding contacts of relay 26' and other intermediate relays (not shown) for other trunks, all for purposes as will hereinafter be described.

The connection of lead 33 to lead 34 completes a circuit for relay 102 as follows: battery, winding of relay 102, lead 34, lead 33, resistance 23, lower inner armature and back contact of relay 15, lower inner armature and back contact of relay 20, armature and front contact of relay 16 to ground. This circuit causes the operation of relay 102 which in turn closes an obvious energizing circuit for relay 104 which in energizing 80 closes an obvious energizing circuit for relay 105. It should be noted that relays 104 and 105 are slow to operate so that an appreciable time interval will elapse before relay 105 is operated after the operation of 85 relay 102. When relay 105 finally operates, a connection is made at its armature and front contact directly to battery from lead 34. This connection shunts the connection from ground at relay 16 to the battery 90 through lamp 18 and relay 102 so that lamp 18 will now become extinguished and relay 102 released. On the release of relay 102, relays 104 and 105 are in turn released. On the release of relay 105 the shunt to battery for lead 34 is removed and lamp 18 is again lighted, and relay 102 is again operated. The reoperation of relay 102 causes the repetition of the above cycle of operations and release of relays 104, 105, 102 and 100 extinguishing of lamp 18, and consequently the closing of a connection between lead 33 and lead 34 will effect continued flashing operations of lamp 18. This lighting and extinguishing of lamp 18 at intervals indicates to the "B" operator that the telephone set 100 is connected to trunk 5, for it will be noted in the following description that simultaneously with the operations just described for the flashing of lamp 18 the connection of the set 100 has actually taken place.

On the connection of lead 22 to lead 31, a circuit was completed for relay 107 as follows: battery, lower armature and front contact of relay 17, upper winding of relay 19, make-before-break contacts of relay 19, leads 22 and 31, armature and back contact of relay 108, armature and back contact of relay 109, winding of relay 107 to ground. This causes the operation of relay 107 which in turn closes an obvious energizing circuit for relay 110. Relay 110 in operating completes a locking circuit for itself through its lower outer armature and front contact to the make-before-break contacts of relay 115 and also completes a connection from a tone source 120 through the primary winding of repeating coil 121, upper armature and back contact of relay 111, upper middle arna-

ture and front contact of relay 110 to ground. Relay 110 also connects the secondary of the repeating coil 121 to the tip and ring conductors of trunk 5 over a circuit as follows: tip conductor of trunk 5, upper inner armature and front contact or relay 26, conductor 29, upper inner armature and back contact of relay 116, upper outer armature and front contact of relay 110, secondary winding of repeating coil 121, upper inner armature and front contact of relay 110, lower inner armature and back contact of relay 116, conductor 30, lower outer armature and front contact of relay 26 and ring conductor of trunk 5. The operation of relay 110 therefore through its connections for the tone source 120 to the tip and ring conductors of trunk 5 causes a tone to be transmitted over the trunk to the outgoing end at the "A" operator's position and, as is well known in the art, this tone is heard by the "A" operator through her telephone set.

The following operations of relays 111, 112, 113, 114, 115 and 116 will cause the alternate removal and application of the tone to the "A" operator's position. These signals serve as an indication to the "A" operator that the "B" operator's telephone set 100 is connected to a trunk 5. The operation of these relays to accomplish this purpose will now be described. It will be noted that on the operation of relay 110, an obvious circuit is completed for the operation of relay 111. The operation of relay 111 opens the circuit through the primary winding of repeating coil 121 from the tone source 120 so that when this relay operates, the tone is removed from the tip and ring conductors of trunk 5. Relay 111 is however, slow to operate so that the tone applied by the operation of relay 110 will be of a sufficient duration to be heard by the "A" operator. On the operation of relay 111 an obvious circuit is closed for the slow-to-operate relay 112. The operation of relay 112 again closes a circuit through the primary winding of repeating coil 121 from ground at its upper armature and front contact through the upper armature and back contact of relay 113 so that when relay 112 operates after a certain period a tone will be again applied to the tip and ring conductors of trunk 5. The operation of relay 112 closes an obvious energizing circuit for the slow-to-operate relay 113 so that before relay 113 operates the tone will have been transmitted to the "A" operator for a period of time of the same length as the period of the first application of tone to the "A" operator. The operation of relay 113 closes an obvious energizing circuit for the slow-to-operate relay 114 which now closes a circuit through the primary winding of repeating coil 121 so that a third ap-

plication of tone is made through the tip and ring conductors of trunk 5 and heard by the "A" operator. On the operation of relay 114 an obvious energizing circuit is closed for the slow-to-operate relay 115. 70 The operation of relay 115 opens the locking circuit for relay 110 previously traced but as relay 107 is still operated, relay 110 will not release at this time. The operation of relay 115 also closes an obvious energizing 75 circuit for relay 116 which in operating opens the connections from the secondary winding of repeating coil 121 to conductors 29 and 30 and trunk 5 and consequently upon the operation of this relay, the third and 80 last application of tone to the "A" operator is removed. The operation of relay 116 now connects at its inner upper and lower armatures and front contacts the tip and ring conductors of the operator's telephone set to 85 the conductors 29 and 30, so that the connection from this operator's telephone set is now completed to the tip and ring conductors of trunk 5.

When the "A" operator receives the above 90 mentioned signals, she will understand thereby that the "B" operator's telephone set is connected to trunk 5 and she will then transmit the number of the wanted subscriber to which the "B" operator is to complete a connection. As the above operations, that is, the connection of the "B" operator's telephone set to the trunk 5, the signaling of the "A" operator and the flashing of lamp 18 take place practically simultaneously, the 95 "B" operator will be prepared for the reception of the number of the wanted subscriber as soon as the "A" operator is ready to give it.

Before proceeding with the description relating to the completion of the connection, 105 a description of the functions of the sequence circuit 10 will now be made. In a case where the operator's telephone set 100 is connected to any engaged trunk other than trunk 5 at the time trunk 5 becomes engaged and it is assumed that the trunk associated with relays 25' and 26' is the one with which the operator's telephone set 100 is engaged the circuits will function as follows: On the engagement of trunk 5, relay 110 is engaged and it is assumed that the circuit for this relay to ground at 27 is broken at the make-before-break contacts of relay 25' so that a connection of the operator's telephone set 100 to trunk 5 cannot take place until it has been disengaged from the trunk associated with relays 25' and 26' and not until the release of relay 25'. On 110 the other hand if, for example, the trunk associated with the relays 25'' and 26'' is the one with which the operator's telephone set 100 is engaged at the time the trunk associated with relays 25' and 26' becomes 115 engaged the circuit for this relay to ground at 27 is closed at the make-before-break contacts of relay 25'' so that a connection of the operator's telephone set 100 to trunk 5 can take place as soon as the trunk associated with relays 25' and 26' is disengaged from the trunk associated with relays 25'' and 26''. On 120 the other hand if, for example, the trunk associated with the relays 25''' and 26''' is the one with which the operator's telephone set 100 is engaged at the time the trunk associated with relays 25' and 26' becomes 125 engaged the circuit for this relay to ground at 27 is closed at the make-before-break contacts of relay 25''' so that a connection of the operator's telephone set 100 to trunk 5 can take place as soon as the trunk associated with relays 25' and 26' is disengaged from the trunk associated with relays 25''' and 26''' and not until the release of relay 25'''.

On the other hand if, for example, the trunk associated with the relays 25'' and 26'' is the one with which the operator's telephone set 100 is engaged at the time the trunk associated with relays 25''' and 26''' becomes 130 engaged the circuit for this relay to ground at 27 is closed at the make-before-break contacts of relay 25'' so that a connection of the operator's telephone set 100 to trunk 5 can take place as soon as the trunk associated with relays 25''' and 26''' is disengaged from the trunk associated with relays 25'' and 26'' and not until the release of relay 25''.

engaged, this latter trunk cannot be associated with the operator's telephone set until relays 26'' and 25'' are released, as relay 26' will be prevented from operating due to the fact that the circuit for this relay will be broken at the make-and-break contact of relay 25''. Another example might be mentioned: In case the operator's telephone set is engaged with trunk 5 and the trunk associated with relays 26' and 25' becomes engaged, the operator's telephone set cannot be connected with this trunk as the circuit for relay 25' will be opened at the inner lower armature and back contact of relay 26 so that relay 25' cannot operate and close the circuit for relay 26'. Also after the operator's telephone set is connected to trunk 5 and the trunks associated with relays 26' and 25' and 26'' and 25'' become engaged while the operator's set is still connected to trunk 5, the trunk associated with relays 26'' and 25'' will be connected to the operator's telephone set first. On the operation of relay 25'' the circuit for relay 26' from ground at 27 will be opened.

Returning now to completion of the connection to the wanted subscriber's line, the "B" operator having received the desired number from the "A" operator inserts plug 30 11 in jack 12 of the wanted subscriber's line 6. If plug 11 is inserted in jack 12 slowly so that the connection through the sleeve terminals are completed prior to the completion of a connection through the tip and 35 ring terminals a circuit will be completed as follows: battery, windings of relay 36 in series, make-before-break contact of marginal relay 37, winding of relay 37, sleeve terminals of plug 11 and jack 12 to ground. 40 The electrical characteristics of relay 37 are such that it will not operate in this circuit, that is with the high and low resistance windings of relay 36 in series in the circuit. Relay 36, however, will operate and a circuit will be closed for relay 38 as soon as the 45 tip and ring terminals of plug 8 have made contact with the corresponding terminals of jack 12. This circuit may be traced as follows: from one side of battery, supplied at 50 the line 6 which may be a subscriber's line or a trunk such as trunk 5 or any other well known type of line having a battery connected to the tip and ring conductors, over the ring conductor of line 6, ring terminals 55 of jack 12 and plug 11, upper armature and back contact of relay 37, winding of relay 38, armature and front contact of relay 36, upper inner armature and back contact of relay 37, tip terminals of plug 11 and jack 12, over the tip conductor of line 6 to the 60 ground at the opposite side of the battery on line 6. This circuit causes the operation of relay 38 which now closes a short circuit to battery for the lower high resistance winding of relay 36. The change in the elec-

trical character of the circuit through relay 37 will now be such that this relay will operate. The operation of relay 37 opens the circuit for relay 38 from the tip and ring conductors of line 6, causing relay 38 70 to release, and this relay also opens the sleeve circuit to relay 36 and closes it through the lower armature and front contact of relay 37 to battery so as to maintain relay 37 energized. Relay 37 also completes the 75 ring conductor from the ring terminal of plug 11 to trunk 5.

Another circuit is closed through the operation of the lower armature of relay 37 for the operation of relays 15 and 19 as follows: battery, lower armature and upper front contact of relay 37, lower winding of relay 19 to ground at the make-before-break contacts of relay 20 and a parallel branch from the battery at relay 37, winding 80 of relay 15 to ground at relay 20. The operation of relay 15 now completes a circuit from the tip conductor of the trunk 5 through the upper winding of relay 16, upper inner armature and front contact of relay 15, upper outer armature and front contact of relay 15, tip terminal of plug 11 thus completing the tip conductor for the trunk around the condenser 39. A similar connection is completed around condenser 40 85 from the ring conductor trunk 5 through the lower winding of relay 16, lower outer armature and front contact of relay 15 to the ring terminal of plug 11. It will be noted that only on the completion of the 90 connection between the tip and ring terminals of plug 11 and corresponding terminals of jack 12 will relay 37 operate so as not to cause relay 15 to operate until the battery on line 6 has actually been connected 95 to the tip and ring conductors of trunk 5. The battery connection for the incoming end of trunk 5 will now, therefore, not be disturbed or broken by the operation of relay 15 but will be immediately extended to the 100 battery on line 6.

The provision of relays 36 and 38 and the marginal operating characteristics of relay 37 therefore prevent any false operation at the outgoing end of trunk 5 should the 105 plug 11 not complete the connection between the tip and ring terminals to the battery on the line 6 simultaneously with the closing of the sleeve circuit on the insertion of the plug 11 into jack 12. In ordinary circuits heretofore, if the tip and ring connection is not extended simultaneously with the sleeve connection, the ordinary relay corresponding to relay 37 might operate and cause the relay corresponding to relay 15 to 110 operate before the connection to battery on a line such as 6 is completed and thus cause an interruption in the battery supplied to the outgoing end of trunk 5. This provision 115 is of particular importance in trunk connec- 120 125 130

tions where the battery supplied to the outgoing end of the trunk line performs some important function at this end such as the holding of certain relays operated for the prevention of premature release of the connection.

The operation of relay 19 mentioned above causes the operator's telephone set 100 to be disconnected from trunk 5, by opening the connection to battery for lead 22 at the make-before-break contacts of relay 19 and by opening the connection to ground for lead 21 at the lower armature and back contact of relay 19. The removal of the ground from lead 21 causes relays 25 and 26 to be returned to normal and the release of relay 26 opens the connection from the common leads 29 and 30 to the trunk 5 and also opens the connection between lead 22 and lead 31 so that relay 107 will now release. On the release of this relay the circuit for relay 110 is opened and this relay is in turn released. The release of relay 110 causes in turn the release of relays 111, 112, 113, 114, 115 and 116 and when relay 116 releases the common conductors 29 and 30 are disconnected from the operator's telephone set 100.

It will be noted that on the release of relay 112, a circuit is completed for the peg-count meter 101 as follows: Battery, winding of peg-count meter 101, upper armature and front contact of relay 115, make-before-break contacts of relay 112 to ground. As stated, the release of relay 112 causes in succession the release of relays 113, 114, 115 and 116 so that when relays 113, 114, and 115 have released, the circuit for the meter is opened. This circuit cannot again be closed until the operator's telephone set 100 is connected with another trunk circuit, that is, until a cycle of operation such as just described for the relays 110 to 115 is again caused to take place due to the operation of relay 107. It will be noted that on the release of relay 107 a short circuit to ground is closed for leads 31 through the upper armature and front contacts of relay 116 to ground at the armature and back contact of relay 107 so that relay 107 cannot again operate until relay 116 has released. This arrangement insures the completion of one cycle of operation of these relays to remove the operator's telephone set 100 from the common leads 29 and 30 before battery on lead 31 that may again be connected thereto, in case another trunk has in the meantime begun the operations for the association of the operator's telephone set 100 with that trunk, will have any effect on the relays mentioned. In accordance with this arrangement, therefore, the operation of the peg-count meter 101 will not take place until the operator's telephone set has been automatically disconnected from the trunk 5 due to the insertion

of the plug 11 into jack 12. The meter 101 cannot therefore be again operated due to any accidental operations that may take place in a trunk connection such as, for example, if the plug 11 is temporarily removed from jack 12. The peg-count meter 101 will register only once for each connection established by a trunk in the group having access to the operator's telephone set 100.

Relays 108 and 109 are provided in conjunction with a key shown below relay 109 to release the operator's set 100 from a trunk, if for any reason the operator cannot complete a connection and the apparatus for automatically performing this function is not brought into play or if it fails to function. On depression of the release key, relay 109 is operated and the connection between lead 31 and relay 107 is broken, thus releasing relay 107 with the result described. Ground is then connected to both windings of relay 108 but as long as a battery connection is maintained over lead 31, relay 108 does not operate since one winding opposes the other. As soon as the battery connection to lead 31 is broken, relay 108 operates through its lower winding and this connection will be maintained as long as the release key is depressed, thus preventing the operation of the release key from being effective on more than one trunk for a single depression of the key. When the key is released, relays 108 and 109 release.

What is claimed is:

1. In a telephone system, a line, a connecting trunk therefor, a relay arrangement for completing a talking connection and maintaining without interruption a certain electrical condition on said trunk, means for operating said relay arrangement responsive to the connection of all of the conductors of the trunk with the corresponding conductors or the line.

2. In a telephone system, a line, a connecting trunk therefor, a relay in the sleeve circuit of said trunk for completing the talking conductors in said trunk, means for operating said relay responsive to the complete connection of all the conductors of the trunk with the corresponding conductors of the line.

3. In a telephone system, a line having its tip and ring conductors connected to ground and battery respectively, a connecting trunk therefor having the incoming ends of its tip and ring conductors connected respectively to ground and battery, a relay arrangement controlled through the sleeve circuit of said trunk and responsive in one manner to the connection of the sleeve conductor of said trunk with the corresponding conductor of the line, a relay, a circuit therefor normally open and bridged across the tip and ring conductor of the trunk, means for closing

said bridge in response to the operation of the relay arrangement in the said one manner, means for operating said relay responsive to the connection of the tip and ring conductors of the trunk with the corresponding conductors of the line, and means controlled by the operation of said relay to control said relay arrangement to operate in another manner so as to remove the ground and battery connections from the tip and ring con-

ductors of the trunk, and connect to said trunk the ground and battery connections of the line without interruption in the supply of current through the trunk from said ground and battery connections. 15

In witness whereof, I hereunto subscribe my name this 7th day of August A. D., 1925.

CLARENCE B. FOWLER.
